Robert H. Weitershausen, INVENTOR.

BY

Geo. P. Kimmel.

ATTORNEY.

UNITED STATES PATENT OFFICE.

ROBERT H. WEITERSHAUSEN, OF PITTSBURGH, PENNSYLVANIA.

TONE-ARM STOP.

Application filed August 4, 1922. Serial No. 579,692.

To all whom it may concern:

Be it known that I, ROBERT H. WEITERSHAUSEN, a citizen of the United States, residing at N. S. Pittsburgh, in the county of Allegheny and State of Pennsylvania, have invented certain new and useful Improvements in Tone-Arm Stops, of which the following is a specification.

This invention relates to a needle positioning and tone arm arresting device for use in connection with phonographs, or the like, and has for its object to provide in a manner as hereinafter set forth, means for conveniently positioning, especially by one with impaired sight, of the needle of the tone arm of a phonograph, or the like, to contact with the record at the proper starting point.

A further object of the invention is to provide a needle positioning and tone arm arresting device for use in connection with phonographs, or the like, with means, in a manner as hereinafter set forth, for limiting the outward throw of the tone arm of a phonograph, or the like, to prevent the shifting of the arm off the record when positioning the needle for engagement with the latter, and which not only facilitates the operation of the machine, but prevents injury to the point of the needle, as is often the case when the needle is positioned to close proximity to the edge of the record, causing it to run off the latter and damage its point.

A further object of the invention is to provide a needle positioning and tone arm arresting device for use in connection with phonographs, or the like, having means, in a manner as hereinafter set forth, which is adjustable so as to enable the employment of the device, to perform its function, with records of various sizes.

Further objects of the invention are to provide a device for the purpose set forth, which is simple in its construction and arrangement, strong, durable, adjustable, readily set up with respect to the tone arm

and record of a phonograph, or the like, efficient and convenient in its use, and inexpensive to manufacture.

With the foregoing and other objects in view, the invention consists of a novel construction, combination and arrangement of parts, as hereinafter more specifically described, and illustrated in the accompanying drawings, wherein is shown an embodiment of the invention, but it is to be understood that changes, variations and modifications can be resorted to, which fall within the scope of the claims hereunto appended.

In the drawings, wherein like reference characters denote corresponding parts throughout the several views:—

Figure 1 is a top plan view of a phonograph or the like, broken away, showing the adaptation therewith of a needle positioning and tone arm arresting device in accordance with this invention.

Fig. 2 is a side elevation of the device,

Fig. 3 is a sectional elevation,

Fig. 4 is a section on line 4—4 of Fig. 3, and

Fig. 5 is a side elevation of a modification.

Referring to Figs. 1 to 4 of the drawings, 1 denotes the casing of a phonograph, or the like, 2 a record of the disc type, 3 a rotatable carrier for the record 2, 4 the pivoted tone arm, and 5 the needle carried by the arm 4.

The device includes a pair of vertically disposed base supporting plates 6, 7, and each of which is formed at its lower end with a flange 8, disposed at right angles with respect thereto, and formed with openings 9 for the passage of securing devices 85 for maintaining the supporting members, 6, 7, fixedly secured in an upright position. The flanges 8, 9, are oppositely disposed with respect to each other. The holdfast devices for securing the flange 8 in position, are indicated at 10. The upper portion of each of the members 6, 7, is offset as at 11, and formed with rows of openings, as illustrated, three rows, but this number can be increased

or diminished as desired. The rows of the openings are indicated at 12, and the openings of one row are staggered with respect to the openings of an adjacent row, and the rows of openings of the plate 6, are arranged in alignment with the rows of openings formed in the offset portion of the plate 7. The openings of the rows of one supporting member or plate are arranged in alignment with the openings of the rows in the other supporting member or plate.

Interposed between the members 6, 7, and extending to the offset portions 11 of said members, is an inverted yoke-shaped element 13, which projects from the forward end of the members 6, 7. The projecting end of the element 13 has a major portion thereof bevelled inwardly as at 14. Positioned in the element 13 and extending forwardly therefrom, is a supporting bar 15, which is spaced from the top 16 of the element 13, thereby providing a guideway 17. The projecting end of the bar 15 is indicated at 18, and said bar 15 is fixedly secured within the element 13, by transversely extending holdfast devices 19, which not only extend through the bar 15, but also through the element 13, and the plates 6, 7. The bar 15 as well as the element 13 in connection with the holdfast devices 19, maintain the plates or members 6, 7, in spaced relation relative to each other.

Slidably mounted on the bar 18 and extended into the guideway 17, is an angle-shaped combined needle positioning and tone arm arresting member consisting of a horizontally extending arm 20 and a vertically disposed arm 21. The arm 20 is mounted on the bar 18 and shiftable thereon. The yoke-shaped element 13 provides means for maintaining the arm 20 in position with respect to the bar 18. The vertical arm 21 is provided with a sleeve 22 which is formed of any suitable cushioning material.

The combined needle positioning and tone arm arresting member is adjustably mounted on the bar 18, and associated with said member, is a means for maintaining it in adjusted position, and such means consist of a lever arm 23, having a bifurcated outer end, as indicated at 24, and which is pivotally connected, as at 25, to the vertical arm 21 of the stop member at a point below the lower end of the cushioning sleeve 22. The rear end of the lever arm 23, is formed with a depending extension 26, disposed at right angles with respect to the lever arm 23, and which is formed at its upper end with a protuberance 27 and at its lower end with a nose 28. To facilitate the shifting of the lever arm 23, when it is desired to adjust the said arm 23, a knob or other suitable device 29, is secured to the lever arm 23 in proximity to the rear end thereof.

The extension 26, of the lever arm 23, is

of a length to seat on the upper face of the top 16 of the element 13, as clearly shown in Fig. 3. The extension 26, is positioned between the offset portions 11 of the members 6, 7, and associates with a stop pin 30, which can selectively engage in any pair of aligning openings of opposed rows of openings 11. The pin 30 is positioned at the rear of the extension 26, and the nose 28, when the extension 26 is co-operating with the pin 30, is extended under the pin, as shown in Fig. 3 in the drawing. The extension 26 in connection with the pin 30, act as means to arrest the rearward movement of the combined needle positioning and tone arm arresting member. Two pins 30, are illustrated, but it is obvious that this number can be increased, or but a single pin used.

The rear corner of the offset portions 11, of the members 6, 7, are connected together by a suitable holdfast device 31.

When using the device, it is secured to the casing 1 of the phonograph, or the like, so that the combined needle positioning and tone arm arresting member will have the sleeve 22 positioned in the path of the arm 4. The combined needle positioning and tone arm arresting member is adjusted to a position, so that when the sleeve 22 is abutted by the arm 4, the needle 5, will be in the desired position with respect to the disc 2. The sleeve 22, is so positioned that it will be impossible for the tone arm, to swing in a direction from off the disc 2, under such conditions preventing injury to the point of the needle 5.

Referring to Fig. 5, which illustrates a modified form of device, the combined needle positioning and tone arm arresting member, as well as the adjusting lever therefor, is constructed in the same manner as that shown in Figs. 1 to 4, and like reference characters as employed in said figures, are also employed in Fig. 5 to designate the elements of said member and its adjusting lever. The modified form shown in Fig. 5, includes a pair of supporting members or plates 32, only one of which is shown, and each of said plates or members 32, is provided with longitudinal rows of openings 33, arranged in the same manner as the rows of openings 11. Mounted between the member or plate 32, is an inverted yoke-shaped element 34, which projects forwardly from the plate or member 32 and extending through said element 34, as well as projecting forwardly therefrom, and also projecting from the rear of the member 32, is a supporting bar 35, the latter having its rear end formed with a right angularly disposed and downwardly extending supporting arm 36, which extends into a socket member 37, the latter carried by a base 38, which is fixedly secured to the casing of the phonograph, or the like.

The arm 36, in connection with the socket 37, supports the device in an elevated position. The bar 35, is spaced from the top of the element 34, to provide a guide passage, 5 and the said bar 35, element 34 and plate 32 are fixedly secured together by holdfast devices 39.

The horizontal leg 20 of the combined 10 needle positioning and tone arm arresting member is mounted in the guide passage formed by the element 34 and bar 35, and is 15 slidable upon said bar 35 to adjust its position. The device shown in Fig. 5 is operated in the same manner as that shown in connection 20 with Figs. 1 to 4.

The form of device shown in Fig. 1, is 25 employed in connection with a Victrola type of machine, or the like, while the form of device shown in Fig. 5, is used in connection 30 with the type of a Columbia machine, or the like.

From the foregoing construction and arrangement of parts, it is obvious that a 35 means is set up, whereby the tone arm of a phonograph, or the like, is arrested so that it cannot be shifted completely away from the record, and that furthermore, the device provides means so that when the stop arm, or rather tone arm, is arrested, the needle 40 carried thereby will be properly positioned with respect to the record. The cushioning sleeve 22 prevents any damage or marring in any manner of the shiftable tone arm, when said arm abuts the combined needle 45 positioning and tone arm arresting member.

The adjustability of the combined needle 50 positioning and tone arm arresting member, enables the device to be used in connection with any type of phonograph, or the like, 55 or in connection with any size record, whether the latter be twelve inch, ten inch, or any other diameter.

What I claim is:—

1. A device for the purpose set forth comprising a supporting means provided with 55 openings, a stop element selectively engaging in certain of said openings, and an adjustable combined needle positioning and tone arm arresting element slidably mounted 60 in said means and co-operating with said stop element.

2. A device for the purpose set forth comprising a supporting means provided with 65 openings, a stop element selectively engaging in certain of said openings, and an adjustable combined needle positioning and tone arm arresting element slidably mounted in said means and having a depending extension co-operating with said stop element.

3. A device for the purpose set forth comprising a supporting means provided with 70 openings, a stop element selectively engaging in certain of said openings, an adjustable 75 combined needle positioning and tone arm

arresting element slidably mounted in said means, and an adjustable lever arm pivotally connected to said element and co-operating with said element.

4. A device for the purpose set forth comprising a supporting means provided with 75 openings, a stop element selectively engaging in certain of said openings, an adjustable 80 combined needle positioning and tone arm arresting element slidably mounted in said means, and an adjustable lever arm pivotally connected to said element and provided with an extension co-operating with said element.

5. A device for the purpose set forth comprising a supporting element, a stop element 85 adjustably mounted in said supporting element, and an adjustable combined needle positioning and tone arm arresting element 90 slidably mounted in said supporting element and co-operating with said stop element.

6. A device for the purpose set forth comprising a supporting element, an adjustable 95 combined needle positioning and tone arm arresting element slidably mounted in said supporting element and provided with an extension, and a stop element adjustably mounted in said supporting element and co-operating with said extension to arrest 100 movement in one direction of said arresting element.

7. A device for the purpose set forth comprising a supporting element, an adjustable 105 combined needle positioning and tone arm arresting element slidably mounted in said supporting element and projecting forwardly therefrom, and a stop element adjustably mounted in said supporting element and cooperating with said arresting element to prevent sliding movement thereof in one direction.

8. A device for the purpose set forth comprising a supporting element provided with 110 rows of openings, said rows of openings disposed on each side of said supporting element, an adjustable combined needle positioning and tone arm arresting element slidably mounted in said supporting element and projecting forwardly therefrom, and a stop 115 element selectively engaging in said openings and co-operating with said element to arrest sliding movement thereof in one direction.

9. A device for the purpose set forth comprising a supporting element provided with 120 rows of openings, said rows of openings disposed on each side of said supporting element, an adjustable combined needle positioning and tone arm arresting element 125 slidably mounted in said supporting element and projecting forwardly therefrom, and a stop element selectively engaging in said openings and co-operating with said element to arrest sliding movement thereof in one direction, said arresting element in 130

cluding a pivoted lever arm formed with an extension co-operating with and projecting below said stop element.

10. A device for the purpose set forth comprising a supporting element provided with a guide passage, an adjustable combined needle positioning and tone arm arresting element slidably mounted in said passage and projecting forwardly from

said supporting element, and a stop element 10 adjustably mounted in said supporting element over said guide passage and co-operating with said arresting element for limiting the sliding movement thereof in one direction.

15 In testimony whereof, I affix my signature hereto:

ROBERT H. WEITERSHAUSEN.
